UNITED STATES PATENT OFFICE.

HENRY LACASSE AND SOL. WILE, OF ROCHESTER, NEW YORK, ASSIGNEES
TO THE BOTTLES' SPECIALTY COMPANY, OF SAME PLACE.

MECHANISM FOR WIRING BOTTLES.

SPECIFICATION forming part of Letters Patent No. 443,194, dated December 23, 1890.

Application filed November 15, 1889. Serial No. 330,257. (No model.)

To all whom it may concern:

Be it known that we, HENRY LACASSE and SOL. WILE, of Rochester, in the county of Monroe, in the State of New York, have invented 55
5 new and useful Improvements in a Mechanism for Wiring Bottles, of which the following, taken in connection with the accompanying drawings, is a full, clear, and exact description.

10 Our invention relates to an improved wiring mechanism, and has for its object the production of a simple and effective device which rapidly and automatically feeds out strands of wire, as desired, and secures them to a 15 suitable article with their extremities projecting therefrom, twists together said projecting extremities, and then severs the wire from the feeding mechanism; and to this end it consists, essentially, in wire-securing jaws 20 of novel and peculiar construction, a lever for forcing said jaws toward and away from the article to be wired, a lever for raising and lowering said jaws, mechanism for rotating the jaws and twisting together the projecting 25 extremities of the wire, a clutch for throwing said twisting mechanism into operation at the desired moment, and wire cutters and 30 holders movable toward and away from the path of the wire-securing mechanism for operating upon the wire and then removing out of the path of the feeding mechanism.

It also consists in the detail construction and arrangement of the parts, all as herein-after more particularly described, and pointed 35 out in the claims.

In describing this invention reference is had to the accompanying drawings, forming a part of this specification, in which like letters indicate corresponding parts in all the views.

40 Figure 1 represents a plan view of our improved wiring mechanism with the feeding mechanism registered with the top of the bottle and the cutting mechanism removed out of the path of said feeding mechanism. Fig. 45 2 is an elevation of one side of the parts as illustrated in Fig. 1. Fig. 3 is a like view to Fig. 2, illustrating the securing-jaws of the feeding mechanism as dropped below the top of the bottle for securing the wire thereto. 50 Fig. 4 is a vertical sectional view on line y y of Fig. 1, showing the mechanism of the wire

holders and cutters. Fig. 5 is an enlarged detail elevation illustrating the securing-jaws in the position assumed after feeding out the wire and twisting together the separate feeding strands. Fig. 6 is a sectional view taken on line x x of Fig. 5, showing the upper part in broken section. Fig. 7 is an enlarged plan of our improved shuttle and wire-securing jaws. Fig. 8 is a horizontal 60 section of the parts illustrated in Fig. 7. Fig. 9 is a longitudinal section of the retaining-pin for the wire-carrier spool of the shuttle. Fig. 10 is a plan view of the bottle, the twisted wire, and the end of the shuttle-jaws. Fig. 65 11 is an elevation of the detached wire cutters and holders. Fig. 12 is a plan view of the parts illustrated in Fig. 11. Fig. 13 is an edge view of the parts shown in Figs. 11 and 12, illustrating particularly the construction 70 of the holding-jaws. Fig. 14 is a section on line 14 14 of Fig. 11, illustrating the cutting-jaws. Fig. 15 is a like sectional view taken on line 15 15 of Fig. 11, illustrating the holding-jaws. Fig. 16 is a sectional view 75 of the mechanism for rotating the shuttle, showing in elevation the clutch for throwing the same into gear. Fig. 17 is a vertical section taken on line 17 17 of Fig. 16. Fig. 18 is a face view of the actuating-gear for rotating the shuttle. Fig. 19 is a face view of the disk locked to the shaft of said actuating-gear. Fig. 20 is a perspective of the locking-dog of the clutch, and Fig. 21 is a perspective view of the head and neck of a bottle 80 wired according to our invention.

Our improved wiring mechanism is mounted upon any suitable supporting-frame A, the one illustrated being the frame of our improved machine for corking bottles and wiring the 90 corks thereto in pending application, Serial No. 319,355. We have, however, illustrated none of the corking mechanism of said improved machine, since our improved wiring-machine may be used with good effect upon 95 other styles of machine than that described and shown in said pending application.

Mounted upon the table A is a suitable bracket B, which supports the shuttle-shaft C. As will be hereinafter described, we prefer to 100 so construct our wiring mechanism that the shuttle-shaft thereof has an up-and-down

movement, and consequently the supporting hub or sleeve b of the shaft C is provided with an arm b' , pivoted at b^2 to said bracket B .

- The shuttle D is of novel and peculiar construction, and consists of a frame D' , a spool D^2 , and yielding wire-securing jaws or arms E . The frame D' is secured to the shuttle-shaft C by means of a set-screw or other suitable means, and is provided with a cut-out, 5 in which is secured the wire spool D^2 . The preferable manner of securing said spool is by means of a pin F , having the head f , which registers with a countersunk shoulder d in the shuttle-frame, and the spring shoulder or dog 10 f' , which engages a countersunk shoulder d' of said frame. This dog f' is mounted in a slot f^2 in the pin F , and is provided with a tooth f^3 , constantly forced outward by means of a spring f^4 . When desired to secure the 15 spool to the frame D' , the same is held in its approximate position, and the pin F is forced into the frame and the central pivotal opening of said spool, whereupon the spring-dog f' is immediately forced inward against the 20 action of the spring f^4 , and when the head f contacts with the countersunk shoulder d the said spring-dog then springs outward and engages the shoulder d' of said frame. It will thus be seen that the spool is very readily 25 mounted in operative position and is securely held by means of the spring retaining-pin. Moreover, the countersunk engaging shoulders of the frame prevent any portion of said pin protruding beyond the frame with the 30 exception, if desired, of the end of the spring-dog f' , which may project a trifle in order to render the same more accessible when desired to force it backward into the slot f^2 in order to remove the spool.
- 35 In operating our improved wiring mechanism it is necessary to use two feeding strands, and in order to render the tension equal upon said strands we preferably wind them both upon the same spool.
- 40 In our Patent No. 406,450 we illustrated a spool in which both strands were wound side by side; but experience has demonstrated that the best results are obtained by providing said spool with a partition D^3 and winding 45 each strand upon the separate divisions of said spool.
- 45 Provided at the forward face or edge of the wire-carrier frame D' is the ear or ears D^4 , to which at e are pivoted the wire-securing jaws 50 E , formed with their forward ends approximated and their adjacent edges rounded from each other in order that the said jaws may readily encircle the top of a bottle or other article to which it is desired to secure the 55 wire. Secured upon the separate jaws E and projecting upon either side of the pivot-points e are shoulders or arms E' , between which and the frame D' are interposed the springs E^2 for approximating the free extremities of 60 said jaws. Formed upon these jaws are stop-shoulders E^3 , normally bearing against the frame D' and preventing the too near approxi-

mation of the free extremities of said jaws. The separate strands of wire are fed through guide-openings d^2 in the frame D' to guides 70 e' in the respective arms and are then twisted together for a short distance beyond the extremities of said arms.

In order to vary the ease of rotation of the wire-spool and the consequent feeding of the 75 wire, we provide the spring e^2 , having one extremity secured to the frame D' and the other bearing against the spool D^2 . A set-screw e^3 , movable in the frame D' , bears against the free extremity of the said spring and forces 80 the same with greater or less force against said spool.

The shuttle is actuated toward the bottle by by a lever G , pivoted at g to an arm A' of the frame A , and as best shown in Fig. 6, this lever 85 is provided with the projecting pin g' , which engages a sliding sleeve or collar C' , locked upon the shuttle-shaft C . Secured to the upper extremity of said lever G is the plate G' , also provided with a projecting pin g' , which 90 engages the opposite periphery of said collar C' . A suitable cam H engages with a stud G^2 , formed upon the lever G , thus forcing said lever backward and forward and operating the shuttle and wire-securing arms toward and 95 away from the bottle. This cam is mounted upon a suitable shaft H' , connected by suitable gearing H^2 to the main shaft H^3 of our improved wiring mechanism. The portion h of the cam H forces forward the lever G , and 100 is preferably so shaped as to act quickly in order to increase the capacity of the machine. Just before the stud G^2 has reached the limit of this portion h the pin or projection i , formed or provided upon the cam H , contacts with a 105 bell-crank lever I , pivoted at i' to a bracket I' , and forces the shuttle-shaft upward in order that the shuttle may be elevated above the top of the bottle. This lever is connected to the shuttle-shaft by the loose sleeve or collar I^2 , pivoted at I^3 to an arm I^4 of said lever I . Immediately after the raising of the shaft C and just before the retraction of the shuttle or wire-carrier the pin i passes from engagement 110 with the lever I , and said shuttle and shaft I^2 then fall downward by gravity, causing the wire-securing jaws to encircle the top of the bottle. The undue downward movement of the shuttle and its shaft is prevented by the contact of the lever I with a pin i^3 , formed upon 115 the bracket I' . During the dropping of the shuttle-shaft the stud G^2 is engaged with the portion h' of the cam H , which is so shaped that said shaft is not withdrawn, and immediately after the dropping of the shuttle-shaft 120 the portion h^2 of the retracting part of the cam H engages said cam, which is so shaped as to retract the shuttle quickly. During this 125 retraction the shuttle-jaws E are forced apart against the action of their springs E^2 and ride around the side of the bottle, catching the wire beneath the ridge thereof, in the plane of which said jaws are then supported. Immediately after the retraction of the shut-

tle-jaws clear of the bottle the shuttle-shaft C is rotated by means of mechanism presently explained, and the separate strands of wire are then twisted together. During the commencement of the operation of the wire-twisting mechanism the stud G² is engaged with the portion h³ of the cam H, which is so shaped as to retract the shuttle but very slowly, if at all, in order that a desired number of tight twists may be made immediately next to the bottle. After the forming of these tight twists the said stud G² is then engaged with the portion h⁴ of the cam H, which is of such form as to retract said shuttle more quickly and cause the wire to be more loosely twisted. After a sufficient length of wire is twisted the wire-holders presently described are engaged with the wire and are impinged thereagainst, whereupon the stud G² is engaged with the portion h⁵ of the cam H, which is so shaped as not to retract said shuttle, in order that a certain number of tight twists may be formed immediately next to the extremities of the shuttle-jaws.

The shaft C is revolved by means of a gear J, provided with a spline or feather sliding in a keyway provided in said shaft, in order that said gear may be constantly engaged during the forward and backward movement of said shaft. This gear engages with a gear K, loosely mounted upon the shaft K' of our wiring mechanism, and is constantly held thereagainst by the back-stop k² or other suitable device.

Suitable gearing K² communicates motion to the shaft K' from the motor-shaft H³, and these separate shafts are suitably timed in relation to each other, so that while the shuttle-shaft is being withdrawn by connection with the shaft H³ the twisting mechanism is operated from the shaft K', and, as presently explained, the wire cutting and holding mechanism is also operated from the shaft H³. As the twisting mechanism is only operated intermittently, it is necessary to provide suitable clutch mechanism to connect and disconnect the loose gear K from the shaft K', which mechanism we will now proceed to describe.

Provided upon the shaft H³ is the cam L, which engages a lever L', pivoted at l to the bracket B. Secured to the shaft K' is the disk or plate K², with which the loose gear K is locked by a suitable clutch device. As illustrated, this clutch consists of a spring-actuated dog L², mounted in a recess K³, provided in the hub of said gear K and secured in said recess by screws. The free extremity of said dog is preferably forced outward by a spring L³, and is provided with the projecting point k and the inclined face k', inclining from said point. When the cam L has forced outward the upper extremity of the lever L', the said dog L² immediately engages the loose gear K with the disk K², whereupon the rotation of the shuttle-shaft immediately commences. When the desired length of wire

has been twisted together, the cam L forces inward the upper extremity of said lever L', which extremity then engages the inclined face k', forcing the same backward and disengaging the tooth or projection k from the disk K². In order to prevent the continued rotation of said loose gear K, which might occur from the momentum thereof, the upper extremity of the lever L' engages a cut-out h³, provided in said gear, and also preferably contacts with the underneath face of the tooth k of the dog L². As previously referred to, after the retraction of the shuttle the wire cutters and holders, which are normally out of the path of said shuttle, as illustrated in Fig. 1, are forced into said path and engage the wire. These wire holders and cutters may be of suitable form or construction, but are here illustrated as jaws mounted upon the separate levers M and N, secured to a pivotal bolt O. The preferable manner of rotating this bolt and swinging the said wire cutters and holders into the path of the twisted wire consists in securing to said bolt a rock-arm P, connected by a link P' to a cross-head R, guided in ways r, formed upon a bracket R', projecting from the frame A. This cross-head is pivoted or otherwise connected to a link S, pivoted at s to a link s', pivoted on the shaft K'. Formed upon the link s' is a projection s², which engages a groove s³, formed in the cam S', mounted on the shaft H³. The central part of the cam S' or the cam-tooth S² of the cam S' forces forward the cross-head R, and the face s⁴, formed upon the groove s³ of the cam, contacts with the projection s² and retracts said cross-head.

The lever M, upon which are mounted the holding-jaw U and the cutting-jaw W, is loose upon its supporting-bolt O; but the lever N for operating said jaws is rigidly secured to said bolt O by any suitable means, and preferably by a square socket engaging a square-shaped portion thereof. The opposite holding and cutting jaws U' and W' are pivoted, respectively, at their upper extremity at u and w to the respective holding and cutting jaws U and W. The lower extremities of these jaws U' and W' are provided with slots u' and w', through which passes the free extremity of the lever N.

When the cross-head R is forced forward, swinging the levers M and N, so that the holding and cutting jaws are engaged with the wire, the forward movement of the lever M is occasioned by means of springs V, secured to the jaws U' and W', mounted on the said lever and bearing against the fixed lever N. After the said wire is engaged with these jaws the lever M contacts with the stop m', formed upon the supporting-bracket m of the bolt O, and prevents the further movement of said lever. The actuating parts of the said cutting mechanism are so arranged, however, that there is still a slight movement of the cross head R, which forces forward the lever N, and this forward movement is al-

lowed by reason of the compression of the springs V. The respective holding and cutting jaws consist of plates sliding one upon the other, and upon this last movement of the lever N the cutting-jaws shear off the wire. The holding-jaws, however, are provided with projecting faces or lugs u² so formed in relation to the cutting-jaws that they do not engage the wire as soon, and therefore merely pinch the same between said jaws u². Immediately after the pinching of the wire by the said holding-jaws the stoppage of the backward movement of the shuttle occurs and the remaining few rotations of the shuttle take place, which form the tight twist immediately next to the shuttle arms or jaws. After the forming of these twists the cross-head is immediately retracted, as described, and the wire cutters and holders are then oscillated out of the path of the wire-shuttle, which is immediately moved forward by the cam H.

As seen in the drawings, we prefer to use two shuttles and so arrange them and their operating mechanism that the wire-securing jaws meet each other at an angle, or, in other words, are movable toward and away from the bottle in lines at an angle with each other. These separate shuttles are preferably operated simultaneously by their connected actuating mechanism, and thus secure the wire to the bottle, with its extremities projecting therefrom at an angle with each other.

The wire holding and cutting mechanism is preferably mounted between the feeding mechanism and is movable toward and away from the same.

The operation of our invention is as follows: The bottle is placed upon its support T. The shuttles are then actuated forward to register the wire-securing jaws with the top of the bottle. The said jaws are then depressed below the top of the bottle, securing the strands of wire to the bottle, with their extremities projecting from one side thereof. The securing-jaws are then retracted around the bottle, and after said retraction the said jaws are rotated, forming tight twists adjacent to the bottle. The said jaws are then retracted to their backward position, feeding and twisting the separate strands of wire. The holding and cutting jaws are then forced to operative position and the securing-jaws rotated to form tight twists adjacent to the shuttle, and, finally, the wire-cutting jaws are operated.

Our improved wiring mechanism applies separated strands of wire to the bottle, with their extremities projecting, and twists together said projecting extremities, as shown in Fig. 21. These projecting extremities are, if desired, afterward turned upward over the top of the bottle; but we have not herein shown or described said mechanism, as we do not wish to be limited thereto.

It will be understood that considerable change may be made in the relative construc-

tion and arrangement of the parts of our invention, and that therefore we do not limit ourselves to its precise form and construction. 7c

Having thus fully described our invention, what we claim as new, and desire to secure by Letters Patent, is—

1. In a shuttle, the combination of a frame, a double spool mounted on said frame and constructed to feed separate ends of wire, a removable pin for normally retaining said spool in its operative position, a spring dog or shoulder for securing said pin to said frame, and a pair of spring-actuated feeding-jaws supported on said frame for feeding said separate strands of wire, substantially as and for the purpose set forth. 75

2. In a shuttle, the combination of a frame, a spool mounted on said frame and having two strands of wire wound thereon, a removable pin for normally retaining said spool in its operative position, a spring dog or shoulder for securing said pin to said frame, yielding jaws for feeding out the wire, a shoulder provided upon each of said jaws, springs bearing against said shoulders, and stop-shoulders for preventing undue movement of said yielding jaws, substantially as and for the purpose described. 90

3. In a shuttle, the combination of a frame, a spool removably mounted in said frame, a removable pin for normally retaining said spool in its operative position, and a spring dog or shoulder removably secured in said pin, whereby the spool is operatively retained on the pin or the pin removed, substantially as and for the purpose specified. 95

4. In a shuttle, the combination of a frame, a spool mounted in said frame, a pin for retaining said spool in its operative position, a yielding shoulder provided upon said pin, and a countersunk shoulder in one wall of said frame for engaging the said pin, substantially as set forth. 105

5. In a shuttle, the combination of a frame, a spool mounted in said frame, forwardly-projecting jaws having a common hinge-point, shoulders extending on either side of said hinge-point, and springs engaging said shoulders, substantially as and for the purpose specified. 115

6. In a shuttle, the combination of a frame having a central opening, a double spool supported in said opening and having separate feeding strands of wire wound thereon, and spring-actuated jaws pivoted to said frame by a common hinge-point for feeding said wire, substantially as and for the purpose set forth. 120

7. In a shuttle, the combination of a frame having a central opening, a spool supported in said opening and having separate strands of wire wound thereon, a pin passing through said spool and removably engaging the side wall of said opening, and spring-actuated jaws pivoted to the forward wall of said opening, substantially as described. 125

8. In a shuttle, the combination of a frame having a central opening, a spool supported

in said opening and having separate strands of wire wound thereon, a pin passing through said spool and removably engaging the side wall of said opening, a spring bearing against said spool for varying its tension, and spring-actuated jaws pivoted to the forward wall of said opening, substantially as set forth.

9. In a shuttle, the combination of a frame, a spool mounted in said frame, and a spring bearing against said spool with projecting shuttle-jaws having a common hinge-point, shoulders projecting on either side of said hinge-point, and springs for bearing against said shoulders, substantially as and for the purpose described.

10. In the shuttle mechanism of a bottle-wiring machine, the combination of a frame, a spool mounted in said frame and having two strands of wire wound thereon, yielding shuttle-jaws provided upon said shuttle and having a common hinge-point, springs for tensioning said jaws, and mechanism for forcing said shuttle toward and away from the bottle, substantially as and for the purpose specified.

11. In the shuttle mechanism of a bottle-wiring machine, the combination of a frame, a spool mounted in said frame, forwardly-projecting jaws having a common hinge-point, shoulders extending on either side of said hinge-point, springs for bearing against said shoulders, and mechanism for moving said shuttle forward and backward, substantially as and for the purpose set forth.

12. In the shuttle mechanism of a bottle-wiring machine, the combination of a frame having feeding-jaws, a wire-carrying spool revolvably mounted in said frame, yielding wire-feeding jaws mounted on said frame by a common hinge-point, a shuttle-shaft, and the lever G, connected to said shaft for forcing the same forward and backward, substantially as and for the purpose described.

13. In the shuttle mechanism of a bottle-wiring machine, the combination of a frame, wire-carrying jaws mounted on said frame and having a common hinge-point, a spool mounted in said frame, a shuttle-shaft, a collar I², through which said shaft is guided, and a bell-crank lever I, loosely connected to said collar for raising and lowering the shaft, substantially as and for the purpose described.

14. In the shuttle mechanism of a bottle-wiring machine, the combination of a frame, wire-feeding jaws mounted on said frame and having a common hinge-point, a spool mounted in said frame, a shuttle-shaft, mechanism for forcing said shaft forward and backward, a loose collar on said shaft, and a lever I, loosely connected to said collar, for actuating the said shuttle-shaft upward and downward, substantially as set forth.

15. In the shuttle mechanism of a bottle-wiring machine, the combination of a frame, a spool mounted in said frame, a shuttle-shaft, mechanism for forcing said shaft forward and backward, a loose collar on said shaft, a lever loosely connected to said collar, a pin i on the

cam H for operating said lever, and a stop i³ for preventing undue movement of said lever, substantially as described.

16. In the shuttle mechanism of a bottle-wiring machine, the combination of a frame, a spool mounted in said frame and having two feeding strands of wire wound thereon, feeding-jaws supported on said frame and having a common hinge-point, and mechanism for rotating said spool, substantially as and for the purpose set forth.

17. In the shuttle mechanism of a bottle-wiring machine, the combination of frames, revoluble spools mounted in said frames, shuttle-shafts arranged at an angle with each other, mechanism, substantially as described, for forcing said shuttle-shafts forward and backward, and mechanism for rotating said shuttle-shafts, substantially as and for the purpose described.

18. In the shuttle mechanism of a bottle-wiring machine, the combination of a frame, a wire-carrier mounted in said frame, a shuttle-shaft, a lever G for forcing said shaft forward and backward, a lever I for forcing said shaft upward and downward, and mechanism for rotating said shaft, substantially as and for the purpose specified.

19. In the shuttle mechanism of a bottle-wiring machine, the combination of a frame, a spool mounted in said frame, wire-feeding jaws pivoted to said frame for feeding the wire, a shuttle-shaft, a lever G for forcing said shaft forward and backward, a cam for operating said lever, and mechanism for raising and lowering said shuttle-shaft, substantially as and for the purpose described.

20. In the shuttle mechanism of a bottle-wiring machine, the combination of supports C, arranged at an angle with each other, means, substantially as described, for moving said supports toward and away from each other, and wire-securing jaws arranged in pairs and mounted on said supports, substantially as and for the purpose set forth.

21. In the shuttle mechanism of a bottle-wiring machine, the combination of supports arranged at an angle with each other, means, substantially as described, for moving said supports toward and away from each other, and wire-securing jaws arranged in pairs and mounted on said supports and disposed in planes one above the other when said jaws are approximated, substantially as and for the purpose described.

22. In the shuttle mechanism of a bottle-wiring machine, the combination of separate shuttles arranged at an angle with each other, yielding wire-securing jaws mounted on said shuttles, and mechanism, substantially as described, for actuating said jaws toward and away from each other, substantially as and for the purpose set forth.

23. In the shuttle mechanism of a bottle-wiring machine, the combination of separate shuttle-shafts arranged at an angle with each other, mechanism, substantially as described,

for moving the shafts toward and away from each other, shuttle-frames mounted on the separate shafts, wire-feeding spools supported in said frames and provided with two feeding strands of wire, and a pair of feeding-jaws supported on each of the separate shuttle-frames, substantially as and for the purpose described.

24. In the shuttle mechanism of a bottle-wiring machine, the combination of separate shuttle-shafts arranged at an angle with each other, shuttle-frames mounted on the separate shafts, a pair of feeding-jaws supported on each of the separate shuttle-frames, and the following mechanisms, to wit: for actuating said shuttle-shafts toward and away from each other and for disposing said wire-feeding jaws in planes one above the other when approximated, substantially as and for the purpose specified.

25. In the shuttle mechanism of a bottle-wiring machine, the combination of supports C, arranged at an angle with each other, means, substantially as described, for moving said supports toward and away from each other, wire-securing jaws arranged in pairs and mounted on said supports, and means, substantially as described, for raising and lowering said supports, substantially as set forth.

26. In the shuttle mechanism of a bottle-wiring machine, the combination of separate shuttles arranged at an angle with each other, means, substantially as described, for moving said shuttles toward and away from each other, separate yielding wire-securing jaws mounted on said shuttles and disposed in planes one above the other when approximated, and means, substantially as described, for raising and lowering said shuttles, substantially as described.

27. In the shuttle mechanism of a bottle-wiring machine, the combination of separate shuttle-shafts arranged at an angle with each other, shuttle-frames mounted on said shafts, wire-carrying spools supported in said frames and provided with two feeding strands of wire, a pair of wire-securing jaws mounted on said frame, and the following mechanisms, to wit: for moving said shafts toward and away from each other and for raising and lowering said shafts, substantially as set forth.

28. In the shuttle mechanism of a bottle-wiring machine, the combination of shuttle-shafts arranged at an angle with each other and wire-securing jaws supported on the separate shafts with the following mechanisms, to wit: for moving said shafts toward and away from each other, for raising and lowering said shafts, and for rotating said shafts, substantially as described.

29. In the shuttle mechanism of a bottle-wiring machine, the combination of shuttle-shafts arranged at an angle with each other and wire-securing jaws supported on the separate shafts with the following mechanisms, to wit: for moving said shafts toward and

away from each other, for raising and lowering said shafts, and for rotating said shafts, and clutch mechanism interposed between said mechanisms for moving the shafts toward and away from each other and for rotating said shafts, whereby said rotation is automatically controlled, substantially as and for the purpose set forth.

30. In the shuttle mechanism of a bottle-wiring machine, the combination of shuttle-shafts arranged at an angle with each other, shuttle-frames mounted on said shafts, wire-carrying spools supported by said shafts, and spring-actuated wire-securing jaws mounted on said frames with the following mechanisms, to wit: for moving said shafts toward and away from each other, for raising said shafts, and for rotating said shafts, substantially as and for the purpose described.

31. In the shuttle mechanism of a bottle-wiring machine, the combination of shuttle-shafts arranged at an angle with each other, shuttle-frames mounted on said shafts, wire-carrying spools supported by said frames, and yielding wire-securing jaws mounted on said frames with the following mechanisms, to wit: for moving said shafts toward and away from each other, for raising said shafts, for 95 rotating said shafts, and for stopping the rotation of said shuttle-shafts when the said wire-securing jaws are in a horizontal plane, substantially as and for the purpose specified.

32. In the shuttle mechanism of a bottle-wiring machine, the combination of a frame, a wire-carrier mounted in said frame, a shuttle-shaft, a gear provided upon said shuttle-shaft, a loose gear engaging the former gear, and a clutch-dog for locking said loose gear 100 to its actuating-shaft, substantially as and for the purpose specified.

33. In the shuttle mechanism of a bottle-wiring machine, the combination of a wire-carrier, a shuttle-shaft, a gear mounted upon 110 said shaft, a loose gear engaging the former gear, a disk fixed to said loose-gear shaft, and a clutch-dog for locking said loose gear and fixed disk, substantially as and for the purpose described.

34. In the shuttle mechanism of a bottle-wiring machine, the combination of a wire-carrier, a shuttle-shaft, a gear mounted upon said shaft, a loose gear for engaging with the former gear, a disk fixed to said loose-gear 120 shaft, a clutch-dog for connecting said loose gear, a second shaft adjacent to the former, a fixed disk upon the latter shaft, and a lever for throwing said dog out of engagement, substantially as and for the purpose specified.

35. In the shuttle mechanism of a bottle-wiring machine, the combination of a wire-carrier, a shuttle-shaft, a gear mounted upon said shaft, a loose gear for engaging with the former gear, a disk fixed to said loose-gear 130 shaft, a clutch-dog for connecting said loose gear, a fixed disk, a lever for throwing said dog out of engagement, a cam for operating said lever, and mechanism for moving said

shuttle-shaft forward and backward, substantially as and for the purpose described.

36. In the shuttle mechanism of a bottle-wiring machine, the combination of a frame, a wire-carrier mounted in said frame, a shuttle-shaft, mechanism, substantially as described, for raising and lowering said shuttle-shaft, a gear provided upon said shuttle-shaft, a loose gear engaging the former gear, and a clutch-dog for locking said loose gear to its actuating-shaft, substantially as and for the purpose specified.

37. In the shuttle mechanism of a bottle-wiring machine, the combination of a wire-carrier, a shuttle-shaft, mechanism for raising and lowering said shaft, a gear mounted upon the shuttle-shaft, a loose gear for engaging the former gear, a disk fixed to said loose-gear shaft, a clutch-dog for connecting said loose gear, a fixed disk, a lever for throwing said dog out of engagement, a cam for opening said lever, and mechanism for moving said shuttle-shaft forward and backward, substantially as and for the purpose set forth.

38. In the shuttle mechanism of a bottle-wiring machine, the combination of shuttle-shafts arranged at an angle with each other and yielding wire-securing jaws supported by each of said shafts with the following mechanisms, to wit: for actuating said jaws forward to encircle the bottle, for actuating said jaws backward from around the bottle, for actuating said jaws backward slowly when clear of the bottle, for then quickly actuating said jaws after their slow retraction, and for rotating the shuttle-shaft during the slow and quick withdrawal of said jaws to form tight and loose twists of the wire, substantially as specified.

39. In the shuttle mechanism of a bottle-wiring machine, the combination of a shuttle-shaft and yielding wire-securing jaws supported by said shaft with the following mechanisms, to wit: for actuating said jaws forward to encircle the bottle, for actuating said jaws backward from around the bottle, for actuating said jaws backward slowly when clear of the bottle, for then quickly actuating said jaws after their slow retraction, for rotating the shuttle-shaft during the slow and quick withdrawal of said jaws to form tight and loose twists of the wire, for stopping the backward movement of the shuttle-shaft, and for rotating the shuttle-shaft after the stoppage of its backward movement to form a tight twist next to the loose twist, substantially as set forth.

40. In the shuttle mechanism of a bottle-wiring machine, the combination of shuttle-shafts arranged at an angle with each other and yielding wire-securing jaws supported by each of said shafts with the following mechanisms, to wit: for actuating said jaws forward to encircle the bottle, for actuating said jaws backward from around the bottle, for actuating said jaws backward slowly when clear of the bottle, for then quickly actuating

said jaws after their slow retraction, for rotating the shuttle-shaft during the slow and quick withdrawal of said jaws to form tight and loose twists of the wire, for stopping the backward movement of the shuttle-shaft, and for rotating the shuttle-shaft after the stoppage of its backward movement to form a tight twist next to the loose twist, substantially as and for the purpose set forth.

41. In the shuttle mechanism of a bottle-wiring machine, the combination of a shuttle-shaft and yielding wire-securing jaws supported by said shaft with the following mechanisms, to wit: for actuating said jaws forward to encircle the bottle, for actuating said jaws backward from around the bottle, for actuating said jaws backward slowly when clear of the bottle, for then quickly actuating said jaws after their slow retraction, for rotating the shuttle-shaft during the slow and quick withdrawal of said jaws to form tight and loose twists of the wire, a cut-off for cutting off the wire between said tight twists, and connected mechanism between the cut-off and the foregoing parts, substantially as and for the purpose described.

42. In the shuttle mechanism of a bottle-wiring machine, the combination of shuttle-shafts arranged at an angle with each other and yielding wire-securing jaws supported by each of said shafts with the following mechanisms, to wit: for actuating said jaws forward to encircle the bottle, for actuating said jaws backward from around the bottle, for actuating said jaws backward slowly when clear of the bottle, for then quickly actuating said jaws after their slow retraction, for rotating the shuttle-shaft during the slow and quick withdrawal of said jaws to form tight and loose twists of the wire, for stopping the backward movement of the shuttle-shaft, and for rotating the shuttle-shaft after the stoppage of its backward movement to form a tight twist next to the loose twist, a cut-off for cutting off the wire between said tight twists, and connected mechanism between the cut-off and the foregoing parts, substantially as and for the purpose specified.

43. In the shuttle mechanism of a bottle-wiring machine, the combination, with wire-securing jaws, shafts arranged at an angle with each other for supporting said jaws, and means, substantially as described, for rotating said shafts and twisting the wire, of cams H, connected to said shafts for actuating the same forward and backward, said cams having portions thereof of varying contour adapted to move the said shafts with varying speed when rotating, substantially as set forth.

44. In the shuttle mechanism of a bottle-wiring machine, the combination of wire-securing jaws, shafts arranged at an angle with each other for supporting said jaws, and means, substantially as described, for rotating said shafts with cams H, connected to said shafts for actuating the same forward and backward, said cams having the portions h,

h', h^2, h^3, h^4 , and h^5 , of different contour, for actuating the said shafts with varying speed, substantially as and for the purpose described.

5 45. In the shuttle mechanism of a bottle-wiring machine, the combination of wire-securing jaws, shafts arranged at an angle with each other for supporting said jaws, and means, substantially as described, for rotating said shaft and twisting the wire, mechanism for actuating the shafts forward and backward with varying speed for varying the twist of the wire, and a clutch interposed between said rotating means and actuating mechanism, substantially as and for the purpose specified.

46. In the shuttle mechanism of a bottle-wiring machine, the combination, with wire-securing jaws, shafts arranged at an angle with each other for supporting said jaws, and means, substantially as described, for rotating said shafts and twisting the wire, of cams H, connected to said shafts for actuating the same forward and backward, said cams having portions thereof of varying contour adapted to move the said shafts with varying speed when rotating, a cut-off for cutting the wire from the wire-securing jaws, and connected mechanism between said cut-off and shaft-actuating mechanism, substantially as and for the purpose set forth.

47. The combination, with wire-securing jaws, shafts arranged at an angle with each other for supporting said jaws, and cams H, connected to said shafts for forcing the same forward and backward, said cams having actuating portions thereof of different contour for varying the speed of the shafts, of the following mechanisms, to wit: for rotating said shafts and for raising and lowering said shafts, substantially as and for the purpose described.

48. The combination of yielding wire-securing jaws, shuttle-shafts arranged at an angle with each other for supporting said jaws, levers G for forcing said shafts forward and backward, cams having actuating portions of varying contour for operating said levers, mechanism for raising and lowering said shuttle-shafts, a cut-off for cutting off the wire, and connected mechanism between said shuttle-shafts and cut-off, substantially as and for the purpose set forth.

49. The combination of a shuttle, a shuttle-shaft, a lever G for forcing said shaft forward and backward, a cam for operating said lever, a lever I for raising and lowering said shuttle-shaft, jaws for holding the wire, mechanism for rotating said shuttle-shaft, and connected mechanism between the foregoing parts, substantially as and for the purpose described.

50. The combination of a shuttle, a shuttle-shaft, a lever G for forcing said shaft forward and backward, a cam for operating said lever, a lever I for raising and lowering said

shaft, cut-off jaws for cutting off the wire, wire-holding jaws for holding the wire, mechanism for rotating the shuttle-shaft, and connected mechanism between the foregoing parts, substantially as set forth.

51. In the shuttle mechanism of a bottle-wiring machine, the combination of supports C, arranged at an angle with each other, means, substantially as described, for moving said supports toward and away from each other, wire-securing jaws arranged in pairs and mounted on said supports, wire-cutters movable into and out of the path of said wire-securing jaws, and connected mechanism between the foregoing parts, substantially as and for the purpose described.

52. In the shuttle mechanism of a bottle-wiring machine, the combination of separate shuttles arranged at an angle with each other, spring-actuated jaws mounted on said shuttles, mechanism, substantially as described, for actuating said jaws toward and away from each other, wire-cutters movable into and out of the path of the wire-securing jaws, and connected mechanism between the foregoing parts, substantially as set forth.

53. In the shuttle mechanism of a bottle-wiring machine, the combination of supports C, arranged at an angle with each other, means, substantially as described, for moving said supports toward and away from each other, wire-securing jaws arranged in pairs and mounted on said supports, separate wire-cutters interposed between said supports and movable into and out of the path of said wire-securing jaws, and connected mechanism between the foregoing parts, substantially as set forth.

54. In the shuttle mechanism of a bottle-wiring machine, the combination of separate shuttles arranged at an angle with each other, yielding jaws mounted on said shuttles, mechanism, substantially as described, for actuating said jaws toward and away from each other, wire-securing jaws arranged in pairs and mounted on said supports, wire-cutters for cutting off the wire, and connected mechanism between the foregoing parts, substantially as and for the purpose set forth.

55. In the shuttle mechanism of a bottle-wiring machine, the combination of separate shuttle-shafts arranged at an angle with each other, shuttle-frames mounted on the separate shafts, a pair of feeding-jaws supported on the separate shuttle-frames, and the following mechanisms, to wit: for actuating said shuttle-shafts toward and away from each other and for disposing said wire-feeding jaws in planes one above the other when approximated, wire-cutters movable into and out of the path of the wire-securing jaws, and connected mechanism between the foregoing parts, substantially as and for the purpose described.

56. The combination of a shuttle, a shuttle-shaft, a lever G for operating said shaft for-

ward and backward, oscillating levers M and N, holding-jaws U U', cutting-jaws W W', mechanism for rotating said shuttle-shaft, and connected mechanism between the foregoing parts, substantially as described.

5 57. The combination of a shuttle, a shuttle-shaft, a lever G for operating said shaft forward and backward, oscillating levers M and N, holding-jaws U and U', cutting-jaws W and W', a cross-head R for operating said levers M and N, mechanism for rotating the shuttle-shaft, and connected mechanism between the foregoing parts, substantially as and for the purpose described.

15 58. The combination of shuttles arranged at an angle with each other, shuttle-shafts, and the following mechanisms, to wit: for rais-

ing and lowering said shafts, for forcing said shafts forward and backward, with oscillating levers M and N, holding-jaws U U', cutting-jaws W W', mechanism for actuating said levers M N, and connected mechanism between the foregoing parts, substantially as and for the purpose set forth.

20 In testimony whereof we have hereunto signed our names, in the presence of two attesting witnesses, at Rochester, in the county of Monroe, in the State of New York, this 10th day of September, 1889.

HENRY LACASSE.
SOL. WILE.

Witnesses:

A. E. PARSONS,
FRANK M. GOFF.
